FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,281,362.

Specification of Letters Patent. Patented Oct. 15, 1918.

Original application filed March 13, 1914, Serial No. 824,429. Divided and this application filed January 15, 1917. Serial No. 142,361.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to typewriting machines or combined typewriting and computing machines, and more particularly to mechanism for effecting the return of the carriage and operation of the general operator of the computing mechanism. In 10 combined typewriting and computing machines of the Underwood-Hanson type in connection with which the present invention is illustrated, the numeral keys operate through suitable mechanism to set up pins 20 connected to rack bars which, when a number has been written, are actuated by a general operator, to run up the number on the computing wheels. The general operator may be driven by an electric motor connected 25 thereto through suitable transmission gearing comprising clutch members adapted to be connected by a clutch shifter which also operates to establish a circuit for the motor so that the general operator is driven 30 through one cycle, the clutch members being then automatically disengaged to disconnect the general operator from the motor.

In accordance with the present invention, the motor may also be used for returning 35 the carriage, and for this purpose, is connected through suitable gearing also comprising a clutch to drive the carriage; a separate switch being utilized to close the motor circuit for the carriage return. Means 40 is provided for automatically actuating the said clutch shifter to connect the motor with the general operator and to close the motor circuit as the carriage completes its forward travel; means also being provided for actuating the clutch between the carriage and the motor when the motor starts, so that the carriage is returned by the motor and the general operator actuated concomitantly. A 45 manual key may also be provided to close the switch for the motor and operate the clutch between the motor and carriage for 50 returning the latter to any intermediate position.

The electric motor is connected through suitable gearing, including a clutch, to a 55 pinion running in mesh with a rack on the carriage for driving the latter. During the forward travel of the carriage, the motor may remain at rest, and as the carriage completes its forward run, said carriage may operate through suitable connections to establish a motor circuit, and thereby start the motor. Right and left hand adjustable margin stops determine the limits of travel of the carriage, and also have connected thereto, cams operated by an arm on the carriage to effect the opening and closing of said clutch at the beginning and completion of the return travel of the carriage. The left hand margin stop is adjustable along a rack 60 bar, which may be swung downward by an arm on the carriage striking a cam connected to said stop, and thereby swing forward a depending arm connected to said rack. Said depending arm moves forward a locking bar to lock the numeral keys, and also moves a latch into operative position to effect the operation of said clutch by the following means. Said latch is vibrated by means of a cam rotated by the motor, so 65 that when the latch is moved to said operative position, its vibratory movement is transmitted to a clutch shifting lever to connect the clutch members, and thereby connect the carriage to the motor. The 70 clutch is therefore operated by power supplied directly by the motor. Connected to the right hand margin stop for adjustment therewith is a cam operated by the carriage at the completion of the return movement, 75 and operable through suitable connections to release the clutch.

The switch for closing the motor circuit as the carriage is completing its forward movement, is connected with the locking bar, 80 which latter, when moved forward, as above stated, operates a bell crank which shifts the switch lever to position to close the circuit and thus start the motor, thereby rotating the carriage-returning gearing and 85 closing the carriage clutch. To maintain the switch lever in this position and thereby keep the motor circuit closed long enough to permit the return of the carriage, the said switch lever is automatically engaged by an arm on a friction ring on the spring 90

drum which propels the carriage in letter-feed direction. When the carriage commences its return, this arm on said ring is brought into contact with the switch lever so as to hold it in position to close the switch. Said friction ring may also operate an arm or projection thereon, into position to lock the tabulating mechanism during the return of the carriage.

10. A manual key for returning the carriage from any intermediate position may be connected to operate said switch lever to close the motor circuit, and may also actuate the said latch for effecting the operation of the clutch between the motor and the carriage. Said manual key may also operate the locking bar to lock the numeral keys.

This application is a division of my application No. 824,429, filed March 13, 1914 (now 20 patent No. 1,238,908).

Other features and advantages will hereinafter appear.

In the accompanying drawings which illustrate one form of my invention as applied to an Underwood-Hanson typewriting and computing machine,

Figure 1 is a part sectional side elevation of the combined typewriting and computing machine.

30. Fig. 2 is a detail view of the switch members associated with the transmission mechanism.

Fig. 3 is a sectional view of the junction box showing the connections between the 35 electric mains and the motor.

Fig. 5 is a sectional side elevation view of the typewriting machine.

40. Fig. 6 is a view similar to Fig. 4 but showing the left hand margin stop and associated parts.

Fig. 7 is a detail view of the clutch releasing trip connected to the right hand 45 margin stop.

Fig. 8 is a rear elevation view of the carriage drum and the means controlled thereby for maintaining the motor circuit closed during the return of the carriage, also of 50 the means for preventing operation of the tabulating mechanism during the carriage return.

Fig. 9 is a detail view of the clutch between the carriage and the motor, and associated parts.

Fig. 10 is a perspective view of the clutch and operating mechanism therefor.

Fig. 11 is a diagrammatic view of the electric circuits.

60. Fig. 12 is a perspective view of a switch and operating mechanism therefor.

Fig. 13 is a rear elevation view partly in section of the combined typewriting and computing machine.

65. The letter keys 1 and the numeral keys 2

are connected to key levers 3 and 4, fulcrumed at 5 and connected through bell cranks 6, to the type bars 7 on a fulcrum rod 8. When a key is depressed, the corresponding type bar is swung upwardly and rearwardly about its fulcrum to bring the types 9 against the printing face of the platen 10. The platen frame 11 is shiftable as usual to upper and lower case positions, and is mounted on a carriage 12 which 75 travels on front and rear guide rails 13 and 14 respectively. Rollers 13^a and 13^b on the carriage run respectively on the rail 13 and the under face of the scale supporting bar 13^c of the machine frame. The roll 15 on the platen frame runs on a shift rail 16 shiftable up and down by the usual mechanism to move the platen to upper and lower case positions. The carriage is driven in letter-feed direction by a spring motor 17 connected through a draw band 18 to the carriage. The letter-feed movement of the carriage may be controlled by the usual letter-feed mechanism, (Fig. 1), comprising escapement dogs 18^c coöperating with an escapement wheel 19, said dogs actuated by a universal bar 20, operated by heels 20^a on the type bars. The operation of the type bars permits a step-by-step rotation of a pinion 21 connected to the escapement wheel 19, said pinion running in mesh with the carriage rack 22, whereby a letter-feed travel of the carriage is effected.

The tabulating mechanism may comprise keys 23 on levers 24, the latter fulcrumed 100 at 25 and having their rear ends extending beneath vertical plunger 26, which when the keys 23 are depressed, are projected upward into the path of column stops 69 on a rack bar 27 on the carriage.

An electric motor M is provided for automatically returning the carriage and for operating the general operator of the computing mechanism. The gearing for driving the carriage from the motor comprises 110 a pulley 28 fixed to the motor shaft 29 (Fig. 13), and connected through a belt 30 to a sheave 31 on a shaft 32, to which shaft 32 is also secured a sheave 33 connected through a belt 34 to a sheave 35 on a clutch shaft 115 36. Fixed to the shaft 36, Figs. 5 and 9, is a member 37 of a clutch which also comprises a member 38 loose on said shaft, and shiftable into and out of engagement with the fixed member 37. Fixed to the shift- 120 able member 38 is a pinion 39 in mesh with a rack 40 on the carriage for returning the carriage and operating the line-spacing mechanism. The clutch is closed to connect the motor M to the pinion 39, in order to 125 return the carriage when the latter completes its letter-feed movement at the end of each line, and said clutch is thereafter opened when the return movement of the carriage is completed, the opening of the 130

clutch being controlled by the right hand margin stop 108, Fig. 4 and its closing by the left hand margin stop 41, Fig. 6.

The margin stop 41 is slidably mounted 5 on a rockable rod or shaft 42, and held in any desired position of adjustment by a rack 43 coöperating with a pivoted dog on the stop, said dog actuated by a finger lever 44. The rack bar 43 is pivoted by means 10 of arms 45 at the ends of the rack bar to rock on the shaft 42 as a fulcrum. The rack bar 43 is held up in its normal position by a coil spring 46, Fig. 4. As the carriage approaches the limit of its forward movement determined by the position of the stop 41, an arm 47, Fig. 6, on the carriage may engage a cam 48 and depress the rack bar sufficiently to operate the signal bell through the usual mechanism, not shown. When the 20 carriage has about completed its forward movement, the arm 47 strikes a cam surface 50 on an arm 51 pivoted at 52 and carrying a roller 53 bearing on the rack bar 43, and further depresses said rack bar. 25 This movement of the rack bar swings forward a depending arm 54 bearing at its lower end against a lug 55 connected to a universal locking bar 56, so that said bar is carried forward beneath the hooks 57 on 30 the numeral key levers 4, and locks said levers. The locking bar 56 during its initial forward movement operates, through a link 58 hooked at its forward end on the locking bar, and is pivoted at its opposite end to a 35 latch lever 59, to move said lever into position to effect the closing of the clutch 37, 38. As the carriage completes its forward movement, the circuit for the electric motor M is closed by means about to be described, 40 so that the motor is running, and the fixed clutch member 37 is therefore rotating at this time. To effect this object, the bar 56 is so disposed as to rest in a longitudinal seat or recess 123^a, formed in the upper face 45 of a rearwardly extending bar 123, (Figs. 5 and 9), which bar is connected through a coil spring 124 to a bell crank 125 pivoted at 126. (Fig. 12.) One arm of this bell crank projects over an extension of a switch 50 lever 99, pivoted at 100 to a conductor 102 and adapted to strike against a contact 101 on a second conductor 103, so as to electrically connect said conductors and thereby 55 close the motor circuit, said switch lever being normally held in open position, however, by means of a controlling spring 107. Bar 56 is normally in contact with the shoulder formed by the front wall of seat 123^a and in consequence when said bar 56 is 60 moved forward, as above described, the bar 123 will likewise be forced forward and will, in turn, actuate bell crank 125, the latter depressing the switch lever 99 and closing the motor circuit. When said circuit is closed, the motor will be started, and

will rotate the clutch shaft 36 through the intermediary of the belt gearing, previously mentioned.

The rear face of the clutch member 37 is formed with a cam 60, (Fig. 9) against 70 which bears the upper end of a bell crank lever 61, fulcrumed on a shaft 62, and having an arm 61^a extending forward from the shaft 62. An arm 63 on the shaft 62 is connected through a spring 61^b to the arm 75 61^a, the movement of the arms 61^a and 63 toward each other being limited by a stop 61^c on the arm 61^a. The bell crank lever 61, therefore, is vibrated by the rotating cam 60, being held against the cam by a spring 80 60^a (Fig. 10), and imparts a vertical reciprocating motion to the latch 59 pivoted on the arm 63. The upper end of the latch is thus vibrated in front of the horizontal arm of a bell crank lever 64 pivoted at 65 to the 85 stationary bracket 66, the latch 59 being in position to clear said bell crank arm 64 when the motor is started. When, however, the carriage, at the completion of its forward run, operates the cam on the left hand margin stop, as above described, to move the locking bar 56 forward, the link 58 draws the upper end of the latch 59 against the bell crank 64, and as the latch is carried downward by the vibrating lever 63, it engages beneath the bell crank 64 so that when the arm 63 again rises, the bell crank 64 is swung about its pivot 65, and a knob 67 on the upper end of the bell crank 64 and which runs in an annular groove 68 in the hub of the pinion 39, carries said pinion rearwardly and connects the clutch members 38, 37. The first part of the rightward movement of the horizontal bar 123, at Fig. 9, serves to swing down the bell crank 125 100 to close the circuit. During the continued motion of said bar to the right, which motion is permitted by reason of the yielding connection 124 between said link 123 and the bell crank 125, the link 58 (which is 105 also connected to the frame 129, 56, moved by the depending arm 54) swings the lever 59 far enough to enable the tip thereof to get under the clutch-closing arm 64 to rock the clutch closed at 37, 38, as shown. It 110 will be understood that the closing of the circuit at 125 causes the motor to start and with the starting of the motor a pulley 35 is turned together with the cam 60, which cam 60 rocks the arm 61^a. Arm 61^a through spring 61^b and stop 61^c moves the arm 63, so that the lever 59 is jigged up and down, and when it is first brought into the down position, it is swung under the clutch-closing arm 64 and moves said arm to clutch-closing 115 position. It will be noted that the clutch member 37, whose cam 60 controls the bell crank 61 which, in turn, controls the bell crank 64 that shifts the loose clutch member 38, is fixed to the clutch shaft 36 to 120 125 130

rotate therewith, and since said clutch shaft is itself driven from the electric motor, it results that the power by which the clutch is thrown in, is supplied directly from the 5 electric motor. The pinion 39 is thus connected to the motor and drives the rack bar 40 to return the carriage. The line-space mechanism may also be operated automatically when the carriage is returned by any 10 approved mechanism.

The means for closing the motor circuit to actuate the hereinafter-mentioned general operator of the computing mechanism will now be described, but it is to be understood, 15 for reasons subsequently explained, that such closing of the circuit does not effect return of the carriage; and is independent of the closing effected by the actuation of the switch 99. A stop 69, Figs. 5 and 13, which 20 is one of a series mounted on the rack bar 27, is provided with a tappet 70 into the path of which projects a cam lug 71 on a lever 72 pivoted intermediate its ends, each stop being adjustable along the rack and preferably positioned to engage the lug 71 upon, or substantially upon, the operation of a key in the units column of a computing zone. The stop 69 shown is positioned to engage said lug shortly before, or just as, 25 the carriage completes its forward travel through a computing zone. The lever 72 operates through a pull link 73 to rotate a bell crank 74, to which is connected one end of a laterally extending bar 75, the other 30 end of which extends over a lever 76, Fig. 1, and when the bar 75 is thus retracted and the lever 76 released, a spring 77 swings said lever about its fulcrum 78, and by means of a pin 79 depresses a rod 80. Said 35 rod rotates a lever 81 about its fulcrum 82, and thereby lifts a stop pin 83 from engagement with a lug 84^a provided on the metallic inner member of a switch disk 92, said member fitting loosely on a cup member 87 which 40 is fixed on a shaft 88. This stop pin, when so withdrawn, releases a clutch-operating ring 84 which operates to rotate disk 92 into position to establish an electric circuit for the motor, and also operates a clutch to connect the motor to the mechanism for driving 45 the general operator. The clutch-controlling ring 84, when released as just described, is rotated by a spring 85 in the direction of the arrow, Fig. 1, to carry a roller 86 upward and jam it between the cam surface of the rim of the cup member 87 and the hub of a worm gear 89 loose on shaft 88, the lateral projection with which said ring is 50 provided bearing against lug 84^a and thereby rotating disk 92, as will be understood. The worm gear 89 is thus connected to the shaft 88, said gear being driven by the worm 55 90 on the motor shaft 29. The metallic outer member or disk 92 (see Figs. 2 and 13) 60 is connected to, but insulated from, the inner

member thereof, and carries contact lugs 91, which lugs 91, as the clutch ring and disk are rotated by the spring 85, engage spring contact arms 93, thereby electrically connecting said arms, and establishing a circuit 70 through the motor M. The motor is thereby started.

The motor operates through the worm gearing 90, 89 to rotate the shaft 88 which is connected to a crank, (not shown), to 75 reciprocate a slide 94 connected to the general operator 95 of the computing mechanism. Said slide is given one complete reciprocation and actuates the general operator through one complete cycle by the time 80 the worm gear 89 has made one complete rotation and is again released from the motor by the stop pin 83 which in the meantime has been returned into the path of the lug 84^a on the switch disk 92.

In order to maintain the motor circuit closed during the return movement of the carriage, the following means is provided. The carriage return drum 17 (see Figs. 8 90 and 13), carries a ring 96 which may be frictionally held in place by springs 97 secured to the drum, and said ring is provided with an arm 98 depending into position to contact with the switch lever 99. Normally the arm 98 is free from the switch lever, but as soon 95 as the carriage commences its return movement, the drum 17 is rotated in a counter-clock-wise direction, Fig. 8, and the arm 98 engages the switch lever which has previously been actuated by the bell crank 125, 100 as will be understood, and prevents it from moving backward. The switch 99 is thus held closed during the return movement of the carriage. By reference to the diagrammatic view of the motor circuits, Fig. 11, it 105 will be seen that the motor circuit is completed through either the switch 92 of the transmission gearing or the switch 99 connecting the conductors 102 and 103, as has already been explained.

The ring 96, Fig. 8, further serves to prevent operation of the tabulating mechanism during the return of the carriage. For this purpose, a projection 104 on the ring 96 when the carriage commences its return 115 movement, is carried into the path of an arm 105 on a rock shaft 106, which may carry a universal locking bar 106^a extending into the path of shoulders or projections on the plunger stops 26, whereby said stops are 120 locked and cannot be operated during the return of the carriage.

When the carriage has been returned, and is released from the returning means, the drum 17 invariably pulls the carriage a short 125 distance forward before the escapement dogs 18^a are in position to hold the carriage. During this slight forward rotation of the carriage drum, the ring 96 is returned to the position shown in full lines in Fig. 13, 130

thereby releasing the tabulator mechanism, and also permitting the switch 99 to be opened by its spring 107. The electric motor M may then remain at rest during 5 the forward travel of the carriage.

As the carriage has about completed its return movement, the clutch 37, 38 is opened by the following mechanism to disconnect the carriage from the motor: Referring to 10 Fig. 4, the right hand margin stop 108 is mounted on the shaft 42 for adjustment longitudinally of the carriage and is held in adjusted position by a rack 109 with which engages a pawl pivoted to the margin stop and 15 operated by a finger piece 110. Connected to the margin stop for adjustment therewith, is an arm 111 splined on the rock shaft 42, and carrying a cam 112 in the path of the arm 47 on the carriage, Fig. 6. The arm 111 20 may be connected to the stop 108 by means of a lip 113 on the stop entering a notch in said arm, such connection permitting the arm to rock with the shaft 42. As the carriage nears the end of its return movement, 25 the arm 47 strikes the cam 112 and rocks the arm 111 and with it, the shaft 42, thereby swinging forwardly a depending arm 114 fixed to the shaft 42. This movement of the arm 114 moves forward a link 115 connecting said arm with a rock arm 116 (see Fig. 30 10), fixed to the shaft 65, and rocks said shaft and with it the bell crank 64 to the Fig. 5 position, thereby separating the clutch members 38, 37 and disconnecting the carriage from the motor.

The carriage may be returned from any intermediate position by depressing a key 117 connected through a pin 118 working in a slot 119 in the machine frame, to an arm 40 120 fixed to a rock shaft 121, to which is also fixed an upwardly extending rock arm 122. To this arm 122 is pivoted the front end of the link or slide bar 123, which latter, as previously stated, is connected through 45 spring 124 to bell crank 125. Spring arm 127 is secured to the rock shaft 121 so that when the key 117 is depressed, the rod 56 is carried forward to lock the numeral keys, and the bar 123 is drawn forward and 50 through the bell crank 125, operates the switch 99 to close the motor circuit. The bar 56 is moved away from key-locking position by the usual spring (not shown). The coil spring 124 is then extended by the continued forward movement of the bar 123 as 55 the key 117 is further depressed to lock the numeral keys as above noted. The forward movement of the locking bar 56 is transmitted through the link 58 to the latch 59, 60 as heretofore explained, to effect the closing of the clutch 37, 38. The arm 127 being elastic or yielding permits the key 117 to be depressed and the motor circuit established independently of the movement of the locking 65 bar 56, which may be prevented from mov-

ing forward on account of the upper end of the latch 59 bearing against the forward end of the bell crank 64, as shown in Fig. 10, until the arm 63 is set in motion by the rotating clutch member 37, and the latch 59 carried downward to position to snap beneath the bell crank 64 as in Fig. 9. It will thus be seen that the key 117 when depressed, first closes the switch to start the motor, and then operates to lock the numeral keys and 70 sets the latch 59 so that the clutch is shifted by the motor. When the key 117 is released, it is returned by a coil spring 118^a, Fig. 9, which may also return the bar 123 and permit the switch 99 to open. It will be noted 75 that the shiftable clutch member 38 is actuated by power supplied directly from the motor M, whether the latch 59 is set by the numeral key 117 or by the carriage operating through the cam on the margin stop. 80 This arrangement provides ample power for operating the clutch and is much more reliable than an arrangement in which the movement of the carriage is relied on to operate the clutch.

The general operator 95 of the computing mechanism is manually controlled by a key 130, Fig. 1, connected to a lever 131 extending over the lever 81 and operable when the key 130 is depressed to actuate said lever and 90 withdraw the holding pin 88, thereby permitting the clutch member 84 and switch disk 92 to operate as heretofore described to close the motor circuit, and also connect the motor through the worm gearing to the driving slide 94 to reciprocate the latter, and thereby actuate the general operator through one cycle.

The numeral keys 2 are provided with pendants or thrust links 132 each adapted to 105 strike an arm 133 on a rocker 134, and cause the latter through a linkage 135 to set up a pin 136 on a rack bar 137, thus moving said pin into the path of the general operator. The bars 137 are positioned by the operation 110 of the numeral keys to be set by selector dogs 138 on the carriage. Each selector dog is provided with a tappet 139, which during the travel of the carriage, comes successively into engagement with the individuals of a 115 series of jacks 140. These jacks depress thrust links 141 and through levers 142 and transposition mechanism 142^a, raise the rack bars 137 to bring the pins 136 thereon into position to be depressed by the pin-setting linkages. The specific form of computing mechanism does not in itself form a part of 120 the present invention, and need not be set forth further in detail.

The typewriting machine frame 144 may 125 be removably supported on the casing 145 which contains the computing mechanism, said casing in turn removably connected to the framework 146 which supports the motor and transmission gearing. To permit the re- 130

moval of the typewriting machine, the lower ends of the electrical contact bars 102, 103 are bent forward as shown in Figs. 5 and 12 and rest on the contact bars 147 and 148 5 in the casing 145, said bars 147 and 148 in turn bearing on the conductors 149 and 150. The conductors 149 and 150 are respectively connected to binding posts 161 and 160 extending into a junction box 151. Electric 10 current from any suitable source is supplied through the main cable 152 comprising a conductor 162 connected with the binding post 160, and a conductor 163 connected to an intermediate binding post 164. A cable 165 15 extending from the junction box 151 comprises conductors 166 and 167 connected to the binding posts 164 and 161 respectively. These conductors 166 and 167 may be connected to the motor terminals. A cable 168 20 leading from cable 165 may carry a wire connecting conductor 167 of the one terminal 93 of the transmission clutch switch, the other terminal of said switch being connected through a conductor 169 in a cable 169^a to the binding post 160.

Variations may be resorted to within the scope of the invention, and portions of the improvements may be used without others.

Having thus described my invention, I 30 claim:

1. In a combined typewriting and computing machine, the combination with a traveling typewriter carriage, of an electric motor for returning said carriage; computing mechanism, gearing between the motor and said computing mechanism, comprising a clutch, 35 a device to actuate said clutch, and operatively connect the motor to the computing mechanism, means operated by the actuation of said clutch to establish a circuit for the motor, means to release said clutch when the computing mechanism has completed a cycle of operations, and means to automatically maintain the motor circuit independently of 40 said clutch until said typewriter carriage has been returned by said motor.

2. In a combined typewriting and computing machine, the combination with a traveling typewriter carriage, of an electric 50 motor for returning said carriage, computing mechanism comprising a general operator, gearing between the motor and general operator comprising a clutch, with a clutch shifter, means operated by the carriage to effect the operation of the clutch shifter, and thereby connect the motor to drive the general operator, a switch actuated by the clutch shifter to establish a circuit for the motor, and a second switch controlled by the return movement of said carriage for automatically maintaining the motor circuit independently of said first-named switch.

3. In a combined typewriting and computing machine, the combination with a

traveling typewriter carriage, of an electric 65 motor for returning said carriage, gearing between said motor and carriage comprising a clutch, computing mechanism, and means, under control of the said carriage, for both automatically operating said computing 70 mechanism and also operating said clutch and connecting the motor to the carriage for returning the latter.

4. In a combined typewriting and computing machine, the combination with a traveling typewriter carriage, and an electric motor, of gearing between the motor and said carriage comprising a clutch, computing mechanism, gearing between the motor and computing mechanism comprising a clutch, 80 and means for automatically actuating said clutches and connecting the said carriage and computing mechanism to be driven by the motor.

5. In a combined typewriting and computing machine, the combination with a traveling typewriter carriage, and an electric motor, of gearing between the motor and said carriage comprising a clutch, computing mechanism, gearing between the motor 90 and computing mechanism comprising a clutch, means for automatically actuating said clutches and connecting the said carriage and computing mechanism to be driven by the motor, a switch automatically operated to establish a circuit for the motor, means to maintain the motor circuit during the return travel of the carriage, and means to automatically open the motor circuit when the carriage has completed its return travel. 100

6. In a combined typewriting and computing machine, the combination with computing mechanism comprising a general operator, of an electric motor, gearing between said motor and general operator comprising 105 a clutch, a clutch shifter, a pin for holding the clutch shifter in inoperative position, a traveling typewriter carriage, means actuated thereby for withdrawing said pin and permitting the clutch shifter to connect 110 the clutch members and thereby effect an operation of the general operator, means to return said pin into the path of the clutch shifter to release the clutch when the general operator has completed a cycle of operations, and a switch actuated by said clutch shifter to establish a circuit for the motor. 115

7. In a combined typewriting and computing machine, the combination with typewriting mechanism including a traveling carriage, and computing mechanism comprising a general operator, of an electric motor, gearing between said motor and general operator comprising a clutch, a clutch shifter, a pin for holding the clutch shifter in inoperative position, means actuated by 125 said typewriter carriage for withdrawing

5 said pin and permitting the clutch shifter to connect the clutch members and thereby effect an operation of the general operator, means to return said pin into the path of 10 the clutch shifter to release the clutch when the general operator has completed a cycle of operations, a switch actuated by said clutch shifter to establish a circuit for the motor, gearing between the motor and said carriage for returning the latter, and means for automatically maintaining the motor circuit during the return travel of the carriage independently of said switch.

15 8. In a combined typewriting and computing machine, the combination with computing mechanism, and typewriting mechanism including a traveling carriage of an electric motor for returning the carriage, a manual key, means operated thereby for effecting a driving connection between the carriage and motor, a second manual key, and means operated by said second key to cause said motor to drive the computing mechanism.

20 25 9. In a combined typewriting and computing machine, the combination with computing mechanism and a traveling typewriter carriage, of a motor, connections from the motor for returning the carriage, separate connections from the motor for actuating said computing mechanism, and means operated by said carriage for controlling both of said connections.

30 35 10. In a combined typewriting and computing machine, the combination with computing mechanism and a traveling typewriter carriage, of a motor, connections from the motor for returning the carriage, separate connections from the motor for actuating said computing mechanism, and means operated by said carriage for controlling both of said connections either separately or concomitantly.

40 45 11. In a combined typewriting and computing machine, the combination with computing mechanism and a traveling typewriter carriage, of a motor, connections from the motor for returning the carriage, separate connections from the motor for actuating said computing mechanism, a margin-gage carried by said carriage for controlling the carriage-return connections, and means also carried by the carriage for controlling the computing-mechanism connections independently of the position of said margin-gage.

50 55 60 65 12. In a combined typewriting and computing machine, the combination with computing mechanism and a traveling typewriter carriage, of a motor, connections from the motor for returning the carriage, separate connections from the motor for actuating said computing mechanism, a margin-gage carried by said carriage for con-

trolling the carriage-return connections, and 65 adjustable means also carried by the carriage controlling the computing mechanism-connections independently of the position of said margin-gage, whereby said computing mechanism may be operated at different 70 column positions of said carriage, dependent upon the adjustment of said means.

75 13. In a combined typewriting and computing machine, the combination with computing mechanism and a traveling typewriter carriage, of a motor, connections from the motor for returning the carriage, separate connections from the motor for actuating said computing mechanism, a left-hand margin-gage for controlling the carriage-return connections, a right-hand margin-gage for controlling the breaking of said connections, and means carried by the typewriter carriage for controlling the computing-mechanism connections independently 85 of either margin-gage.

80 90 14. In a combined typewriting and computing machine, the combination with computing mechanism and a traveling typewriter carriage, of a motor, connections from the motor for returning the carriage, separate connections from the motor for actuating said computing mechanism, a left-hand margin-gage for controlling the carriage-return connections, a right-hand margin-gage for controlling the breaking of said connections, and a tabulator-stop carried by the carriage for controlling the computing-mechanism connections independently of 95 either margin-gage.

100 105 15. In a combined typewriting and computing machine, the combination with computing mechanism and a traveling typewriter carriage, of a motor, connections from the motor to said carriage for returning the same, including an electric-circuit, connections from the motor to said computing mechanism independent of said circuit, and means operated by the carriage for controlling said circuit and also the computing- 110 mechanism connections.

115 110 120 16. In a combined typewriting and computing machine, the combination with computing mechanism and a traveling typewriter carriage, of a motor, connections from the motor to said carriage for returning the same, including a circuit, connections from said motor to said computing mechanism, including a circuit independent of said first circuit, and means operated by the typewriter carriage for controlling both said circuits.

125 17. In a combined typewriting and computing machine, the combination with computing mechanism and a traveling typewriter carriage, of a motor, connections from the motor to said carriage for returning the same, including a circuit, connections from

- 5 said motor to said computing mechanism, including a circuit independent of said first circuit, and means separately adjustable along said carriage for controlling said circuits, respectively.
- 10 18. In a combined typewriting and computing machine, the combination with computing mechanism and a traveling typewriter carriage, of a motor, connections from said motor to said carriage for returning the same, connections from said motor to said computing mechanism, including a circuit, and means controlled by said carriage for closing said circuit a plurality of times during a single traverse of said carriage and for controlling said carriage-return connections at the completion of its traverse.
- 15 19. In a combined typewriting and computing machine, the combination with computing mechanism and a traveling typewriter carriage, of a motor for driving said computing mechanism and returning said carriage, a circuit for said motor, a second circuit for said motor, means controlled by said carriage for closing both circuits at the same or at different times to enable said motor to return said carriage and actuate said computing mechanism, and means for maintaining both circuits closed until said motor has completed its work.
- 20 20. In a combined typewriting and computing machine, the combination with computing mechanism and a traveling typewriter carriage, of a motor for driving said computing mechanism and returning said carriage, a circuit for said motor, a second circuit for said motor, means controlled by said carriage for closing both circuits at the same or at different times to enable said motor to return said carriage and actuate said computing mechanism, and means individual to each circuit for maintaining said circuits closed until said motor has completed its work.
- 25 21. In a combined typewriting and computing machine, the combination with computing mechanism, and typewriting mechanism including a carriage, of a frame for said typewriting mechanism, a frame for said computing mechanism, mechanism for returning the typewriter carriage carried by said typewriter frame, mechanism for actuating the computing mechanism carried by said computing frame, a motor for driving both said actuating mechanism and said returning mechanism, also carried by said computing frame, and electrical connections controlled by said typewriter carriage and closing the circuit to said motor, said electrical connections being automatically separable so that said connections may be rendered operative by the mere placing of one machine frame upon the other.
- 30 22. In a combined typewriting and computing machine, the combination with computing mechanism, and typewriting mechanism including a carriage, of a frame for said typewriting mechanism, a frame for said computing mechanism, mechanism for returning the typewriter carriage carried by said typewriter frame, mechanism for actuating the computing mechanism carried by said computing frame, a motor for driving both said actuating mechanism and said returning mechanism, also carried by said computing frame, and electrical connections controlled by said typewriter carriage and closing the circuit to said motor, said electrical connections being separable and including spring-fingers carried by one of said machine frames, and a contact-plate carried by the other of said frames to be engaged by said spring-fingers when said frames are placed one upon the other.
- 35 23. In a combined typewriting and computing machine, the combination with a typewriter carriage, of an electric-motor for driving said carriage in one direction, computing mechanism, a switch controlled by the carriage for establishing a circuit for the motor and causing the latter to effect the accumulating action of said mechanism, a second switch set by said carriage on reaching a predetermined position, for returning the carriage, and means for maintaining said circuit for the motor until the carriage has been returned, independent of the first-named switch.
